(57) **CLAIM**

The ornamental design for a foldable solar panel, as shown and described.

DESCRIPTION

FIG. 1 is a front, right, and top perspective view of a foldable solar panel, showing our design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1.

FIG. 10 is a partial enlarged view of an area labeled 10 in FIG. 1.

FIG. 11 is a partial enlarged view of an area labeled 11 in FIG. 1; and,

FIG. 12 is a partial enlarged view of an area labeled 12 in FIG. 1.

The broken lines shown in the drawings are included for the purpose of illustrating portions of the foldable solar panel that form no part of the claimed design.

1 Claim, 12 Drawing Sheets
